J. C. KITTERMAN

UMBRELLA CASE

Filed April 17, 1924

Inventor
Jesse C. Kitterman

By *Harold A. Mueller*

Attorney

UNITED STATES PATENT OFFICE.

JESSE C. KITTERMAN, OF CORYDON, INDIANA, ASSIGNOR OF ONE-HALF TO RUSSELL R. ROWE, OF CORYDON, INDIANA.

UMBRELLA CASE.

Application filed April 17, 1924. Serial No. 707,174.

To all whom it may concern:

Be it known that I, JESSE C. KITTERMAN, a citizen of the United States, residing at Corydon, in the county of Harrison, State of Indiana, have invented certain new and useful Improvements in Umbrella Cases; and I do hereby declare the following to be a full, clear, and exact description of the invention, such as will enable others skilled in the art to which it appertains to make and use the same.

This invention relates to new and useful improvements in umbrellas, and particularly to cases therefor.

One object of the invention is to provide a case for an umbrella which renders the same serviceable as a cane.

Another object is to provide a device of this character wherein the case is adapted to be telescoped and secured to the stick of the umbrella to form the handle of the umbrella.

Another object is to provide a device of this character wherein the umbrella serves as a brace to maintain the casing in extended position, and against collapsing, when the case is being used as a cane.

Other objects and advantages will be apparent from the following description when taken in connection with the accompanying drawing.

In the drawing:

Figure 1 is an elevation of the casing when used as a cane, and with the umbrella therein.

Figure 2 is a longitudinal sectional view through the cane, in the position of Figure 1, the umbrella being shown in elevation.

Figure 3 is an elevation of the umbrella with the cane collapsed and attached to the stick of the umbrella to form the handle thereof.

Figure 4 is a longitudinal sectional view through the handle.

Referring particularly to the accompanying drawing, 10 represents an umbrella which has the metal stick 11, and the tip and ferrule 12 and 13 on the end thereof. Secured on the handle end of the stick 11 is a metal cup 14, the open end of which is directed away from the umbrella and is internally threaded.

The casing or cane portion of the device

comprises a plurality of telescoped tapering tube sections 15, the smallest end section 15' being provided, in its outer end, with a metal tip 16. The other end section 15² is externally threaded at its opposite ends, as at 17 and 18, respectively. The umbrella is adapted to be inserted into the sections of the casing, as shown in Figure 2, the tip 12 entering the section 15' until the ferrule 13 rests against the inner end of said section. The metal cup 14 passes wholly within the largest end section 15², and when the cap 19 is screwed onto the threaded end 17, of said section, said cap will bear against the outer end of the cup, with the result that the portion of the umbrella between the ferrule 13 and the outer end of the cap 19 effectively braces the telescopic sections to maintain them in proper extended position, with the result that the casing, with the umbrella therein, serves as a cane without danger of accidentally collapsing.

When the umbrella is to be used, the cap 19 is unscrewed from the section 15², and the umbrella pulled from the casing. The casing is then collapsed and the cup 14 screwed onto the smaller end of the section 15², while the cap 19 is screwed onto the larger end of said section, again. The intermediate sections 15 lie within the section 15², while the section 15², together with the cup 14 and cap 19, form a neat and durable, as well as convenient handle for the umbrella.

What is claimed is:

1. A combined cane and umbrella case comprising a casing including telescopic sections the larger end one of which is externally threaded at both ends, said sections, when extended receiving the umbrella, an internally threaded cup fixed on the handle end of the stick of the umbrella and arranged to receive one end of said larger end section when the sections are telescoped, and a cap arranged to be engaged on the other end of said larger end section when the sections are collapsed, at times, and when the sections are extended, at times.

2. A combined cane and umbrella case comprising a casing composed of telescopic sections the larger end one of which is externally threaded at both ends, an internally threaded cup member fixed on the handle

end of the stick of the umbrella and arranged to receive one end of said larger end section when said sections are telescoped within said end section, and a cap removably engaged on the other end of said end section for engagement with said cup member to retain the umbrella within the casing and to hold the casing extended, at times,

and for holding the sections telescoped within said section, at times.

10

In testimony whereof, I affix my signature, in the presence of two witnesses.

JESSE C. KITTERMAN.

Witnesses:

RUSSELL R. ROWE,
CONRAD LUTTICK.
